(57) **CLAIM**

The ornamental design for a ratcheting stubby wrench handle, as shown and described.

DESCRIPTION

FIG. 1 is a right side perspective view of the ratcheting stubby wrench handle of the present invention showing the new design;

FIG. 2 is a left side perspective view thereof;

FIG. 3 is a top plan view thereof;

FIG. 4 is bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines in the drawings illustrate environmental structure and form no part of the claimed design.
